HEATING OF FLUIDS

Marion W. Barnes, Chicago, Ill., assignor to Universal Oil Products Company, Chicago, Ill., a corporation of Delaware

Application January 26, 1942, Serial No. 428,241

1 Claim. (Cl. 122—250)

This is a continuation-in-part of my copending application Serial Number 236,681, filed October 24, 1938.

The invention relates to the heating of fluids and more particularly to a heater in which separate streams of fluid, either in liquid, vaporous or mixed phase, may be quickly heated to the desired temperature while undergoing only a relatively small pressure drop.

The features of the present invention provide means for obtaining efficient and rapid heating of fluids in a heater for which the maintenance, as well as the installation costs, are exceptionally low.

The heater herein provided may be advantageously employed in processes where relatively small quantities of fluid are to be heated to moderate temperature, such as for instance in the heating of normally gaseous hydrocarbon charging stock for a catalytic polymerization process, to form gasoline fractions of high antiknock value from olefinic components thereof. My invention may also be advantageously employed as a reboiler heater for supplying heat to the various columns employed in fractionating and gas concentration systems and the like.

In designing heaters for the class of service contemplated by the invention, pressure drop is an important item to be considered. By employing a heater of the improved type provided by the invention a considerable reduction in pressure drop is obtained as compared with that encountered in conventional heaters now employed for such service. In processes wherein pumps, compressors or blowers are required to force the fluids to be treated through the heater, the size of such equipment, and therefore the cost of installation, as well as operation and maintenance, is directly dependent upon the resistance encountered by the fluids in traversing the heater. In previous heaters this resistance to the flow of fluids through the heater has been governed by the size of the fluid conduit. It is well known that small size heating conduits give better rates of heating, other conditions being comparable, than larger diameter tubes, because of their greater heating surface per unit volume. Also, more uniform heating of the entire stream is obtained throughout the cross-sectional area of the conduit with smaller tubes.

The features of my invention provide a compact heater which is simple to construct and at the same time offers the advantage of efficient and rapid heating of fluids to the desired temperature without excessive pressure drop by utilizing relatively small fluid conduits disposed in parallel flow arrangement.

The accompanying diagrammatic drawings illustrate two specific forms of apparatus embodying the features of the invention.

Figure 1 of the drawings is an elevational view, shown principally in cross-section, of one form of heater provided by the invention.

Figure 2 is a cross-sectional view of the same heater taken along a plane indicated by line 2—2 in Figure 1.

Figure 3 is an elevational view, shown partially in section, of a modified form of the invention.

Referring to Figures 1 and 2, the main furnace structure comprises an outer wall 1, a roof 2 and a floor 3. The walls, roof and floor are constructed of suitable refractory material which may, for example, be fire-brick shapes or one of the several types of materials which are placed in semi-solid or plastic form and upon hardening or setting possess good refractory characteristics. A suitable metallic shell or housing 4 encases the refractory walls, roof and floor of the furnace and this housing extends, as indicated by 5, beneath floor 3 and is anchored to a suitable foundation 6, a space 7 being provided between floor 3 and the foundation. The upper portion of housing 4 converges to and supports a stack 8, which is provided with a suitable damper 9.

The fluid conduit through which the fluid undergoing treatment is passed comprises a tubular coil 10 having several helical turns and a plurality of flat spiral coils 11 disposed above the coil 10. The coil 10 is a single helix and the fluid undergoing treatment passes through the turns of the helix in series. The coils 11 comprise a plurality of superimposed flat spiral coils arranged for the parallel flow therethrough of two separate streams of fluid of substantially equal volume. The coils 11 and 10 are interconnected in series.

The central portion of the heater, within which coil 10 is disposed, comprises a combustion and heating zone 12 and the tubular turns of the coil are located relatively close to the circular wall 4 of the heater, leaving an unobstructed space within the coil and heater for the efficient combustion of fuel and for the upward passage of flames and hot gases resulting from such combustion.

The flat spiral coils 11 are disposed within the upper portion of the heater directly above the combustion and heating zone 12 and the tubular members of these coils are located within the direct path of travel of hot combustion gases from zone 12, being intimately contacted with the gases during passage of the latter from the combustion zone 12 to the stack 8.

A gas burner 14 which, in the case here illustrated, is supplied with a gaseous fuel through line 15 and valve 16 is provided within space 7. It is entirely within the scope of the invention to employ burners of other types than that shown

which are suitable for use with other forms of fuel, such as, for instance, fuel oil, when desired. Regulated quantities of air for combustion are admitted to the space 7 through the opening 17 in shell 5, control of this air being obtained by movement of the sliding damper 18. In the burner here shown, a portion of the air for combustion is admitted thereto through a suitable mixing device 19, and the combustible mixture, after passing through the Venturi section 14, is discharged from the burner nozzle through the port 20 into the combustion zone 12 where it is admitted through opening 11, passes through space 21 between the burner tip and the firing block 22 and burned. Additional air for combustion commingles, in passing through firing port 20 with the fuel-air mixture from the burner, passing therewith into the interior of the heater. The block 22 is made of suitable refractory material and supported by the floor 3 and shell portion 4. A checker-work 23, made up of fire-brick or the like, is provided immediately above burner port 20 to diffuse the flame and give more uniform distribution of the radiant heat.

The flames and hot combustion gases are directed upwardly from the burner port 20 and the checker-work 23 through the heating zone 12 and a substantial portion of their heat is given up, by direct radiation and convection to the tubular coil 10. The hot gases continue upwardly, passing in direct and intimate contact with the tubular elements 11, comprising coils to which fluid heat is supplied from the combustion gases. The products of combustion are finally directed through the stack 8 to the atmosphere.

The supporting means for the coils 10 and 11 are the subject of my aforementioned co-pending U. S. application Serial Number 236,681, filed October 24, 1938, and comprise, in the instance herein illustrated, three vertically disposed tubular elements 24, approximately equally spaced on a circle somewhat larger in diameter than that about which the tubular element of coil 10 is wound. The several turns of coil 10 may be secured to the elements 24 by means of U-bolts 25, as shown, or the coil 10 may be welded or otherwise suitably attached to the supports. Radial members 26, attached to the upright elements 24 by bolts or other suitable means, serve to support the flat spiral coils 11. The lower ends of elements 24 rest upon the foundation 6, and are provided with openings 28 therethrough adjacent their lower ends within zone 7.

The natural draft created in the furnace and acting upon the open upper ends of the tubes serves as a means of drawing air from the space 7, into and through the interior of the tubes, thereby cooling them. When desired, insulation, as shown, may be provided around the supporting elements 24 in the lower portion of zone 12 where they are exposed to extremely high temperatures.

The upper end of coil 10 is connected by means of the tubular conduit 30 to the two lowermost flat spiral coils 11 and the alternate coils 11 are then each connected in series by means of conduits 31, 32, 33 and 34 to provide two substantially equal paths for the flow of fluid being heated. The inner ends of the two uppermost coils 11 are connected by conduits 35 and 36 to the conduit 37. By arrangement here illustrated, assuming the flow of fluid is in a generally upward direction, the stream would enter the

heater at the lower end of coil 10, absorb substantial quantities of radiant and convection heat and then by means of conduit 30, will be divided into two substantially equal streams. One of said streams will flow through the lowermost coil 11, then by means of conduit 31, will be directed into the third from the lowermost coil 11, through which it will flow and be, in turn, directed by means of conduit 33, to the fifth coil from the lowermost coil 11 through which it will pass and be directed by conduit 35, to conduit 37 where it will be joined by the other stream which has in the meantime passed serially through the remaining individual coils 11. Flow in the reverse or generally downward direction through the heater, which is also contemplated by the invention will be apparent without detailed description.

Referring now to Figure 3, the heater here illustrated is of the same general form as that illustrated in Figures 1 and 2 and corresponding portions thereof are designated by the same, reference numerals.

The essential difference between the heater shown in Figure 3 and that shown in Figures 1 and 2 resides in the arrangement of the tubular elements disposed about the heating zone 12. The heater shown in Figure 3 embodies a parallel arrangement of these coils, which comprise two helical shaped tubular elements 10' and 10'' which are disposed about the heating zone 12 and are heated by radiant and convection heat. The flat spiral coils of the upper tube bank 11 are similar to those shown in Figures 1 and 2 and alternate coils are serially connected by means of conduits 30', 30'', 31', 32', 33', 34', 35' and 36' to provide parallel paths of flow for two separate streams of fluid. Coil 10' is connected by means of conduit 30' in series with the lowermost coil of bank 11 and consequently with each alternate higher coil of this bank. Coil 10'' is connected by conduit 31' in series with the second from the lowermost coil of bank 11 and with each alternately higher coil of this bank. Thus, two separate parallel paths are provided for the passage of fluid through the fluid conduits of the heater.

It is entirely within the scope of the invention to employ more than two parallel streams illustrated in the accompanying diagrammatic drawings by providing more flat spiral coils and more than two helical coils.

I claim as my invention:

A heater comprising, in combination, a vertically disposed, substantially cylindrical, refractory wall defining a radiant heating zone and a fluid heating zone disposed above and in direct communication with said radiant heating zone, a pair of tubular fluid conduits, each comprising a plurality of helical turns, disposed in said radiant heating zone adjacent the surface of said wall, a first set of superimposed and serially connected flat spiral coils disposed in said fluid heating zone and communicating with one of said conduits, a second set of superimposed and serially connected flat spiral coils disposed in horizontal planes alternating with the horizontal planes of the coils of said first set and communicating with the other of said conduits, means for projecting hot combustion products upwardly through said heating zones, and means for supplying a stream of fluid to each of said conduits.
